UNITED STATES PATENT OFFICE

ISIDORE SIMON, OF CHICAGO, ILLINOIS

COMPOSITION HEEL

Application filed June 13, 1927. Serial No. 198,451.

My invention belongs to that general class of devices known as heels and relates more particularly to a light weight composition heel for shoes, the same being especially adapted for use on ladies' shoes. Heels for ladies' shoes have heretofore been made of wood and suitably covered with leather or fabric or have been otherwise treated and polished to produce a finished heel, and also 10 been produced of compositions, but when so constructed are of such over-weight as to render them objectionable or are so constructed when of composition that they are expensive to make and of short life. My invention has particularly among its objects 15 the production of a heel for shoes that is simple, durable, attractive, inexpensive, of light weight and easily manufactured. It has particularly as an object the production 20 of a heel which will have the advantages possessed by wooden heels of being light weight and easily attached to the shoe and to which a leather or other lift may be conveniently secured. It also has as an object the production 25 of a heel which will have the advantage gained by using a composition such as a phenolic condensation product, which may be easily molded, which will not absorb moisture, which may be made in any desired 30 color or combination of colors, and may have a high polish or finish with substantially no special treatment for the production of such finish. Many other objects and advantages 35 of the construction herein shown and described will be obvious to those skilled in the art from the disclosure herein given.

To this end my invention consists in the novel construction, arrangement and combination of parts herein shown and described, 40 and more particularly pointed out in the claims.

In the drawings, wherein like reference characters indicate like or corresponding parts:

45 Fig. 1 is a top plan view of a heel embodying the invention;

Fig. 2 is a cross-sectional view taken substantially on line 2—2 of Fig. 1; and

50 Fig. 3 is a sectional view taken substantially on line 3—3 of Fig. 1.

Fig. 4 is a view in elevation of the upper end of the base 10, a portion of the sleeve 12 broken away.

Referring to the drawings, in which one embodiment of the invention is shown, 1 represents a body part of a phenolic condensation product or other material which may be molded to the desired size and shape and which may be so constituted as to be of the desired color or colors. The same is molded 55 in any suitable manner preferably with a tubular bore 2 with one end as at 3 constructed to form the bottom or underface and the opposite end or top as at 4 to fit and to be secured at the bottom of a shoe. The same is also preferably recessed or molded with shoulders 5 and 6 at the top and bottom so that it is substantially countersunk. Arranged to closely fit the ends at the recessed 60 portions and abut on the shoulders 5 and 6 are the top and bottom plates 7 and 8. These plates are preferably constructed of wood, shaped to fit in the countersunk ends and to conform to the contour at the ends. The top 65 plate 8 is formed with a curved upper face 9 so that with the end face 4 and the body 1, the same is substantially of cup-shaped or depressed shape so as to receive the heel portion of the body of the shoe and conform thereto. Connecting the plates 7 and 8 is a 70 post 10 also preferably of wood, the same being arranged to secure the plates 7 and 8 together and maintain them on the shoulders 75 5 and 6 so that the plates and body 1 constitutes substantially a unitary structure. In the drawings, I have illustrated the post 10 provided with sleeves 11 and 12 at the ends, these being preferably of metal such as brass, or the like and are secured to the post by indenting same as at 13, or otherwise securing the same so that they are not easily removable 80 from the post. The post is so arranged that when the post is inserted as shown in Figs. 2 and 3, the ends of the same lie flush with the outer face of the plates 7 and 8. The sleeves 11 and 12 are arranged on the same but projecting slightly beyond as shown in Fig. 4, there being sufficient material to form flanges 14. After the body 1, plates 7 and 8 and post 10 are assembled, the ends of the 85 90 95 100

sleeves are crimped or bent over as shown in Figs. 2 and 3 to engage the outer faces of the plates which are preferably slightly countersunk to receive them. When so constructed, 5 the several parts are firmly and readily, as well as substantially, permanently secured together, providing to all purposes, the unitary structure.

The heel may be secured to the shoe by 10 driving nails through the sole of the body of the shoe which rests in the cupped end as indicated in dotted lines in Fig. 2, a lift or back portion 15 being also suitably secured by nails or the equivalent to the bottom 15 plate 7.

Ordinarily the use of a phenolic condensation product as a material for heels is not satisfactory as the same is too heavy for the purpose, although it is ideal insofar as being 20 moisture-proof, capable of being colored or tinted as desired and capable of receiving a high polish or finish. It is also undesirable from the point of attaching the same to the shoe body. By constructing the heel as herein 25 set forth, all of the advantages of a phenolic condensation product or like material heel is secured without any of the disadvantages. My improved heel may be made as light as a wooden or the like heel. It may be readily 30 secured to the shoe and the lift 15 readily secured to the underface of the heel. The parts are held in assembled relation in such manner that the fastenings are not affected by moisture or wear nor will they come apart. The 35 heels may be made in various sizes and shapes and in fact, in many sizes and in many instances, standard size plates 7 and 8, may be employed by standardizing the countersunk recesses at the ends. Same is adapted for 40 women's, men's or children's shoes. The parts may be made up in quantity and assembled by more or less unskilled help. While in composition suitable material may be employed for the body 1, I prefer to employ a phenolic 45 condensation product or some combination that has the characteristics of a phenolic condensation product as it is easy molding, has durability, is moisture-proof and capable of receiving a high finish in any desired color. 50 Having thus described my invention, it is obvious that various immaterial modifications may be made in the same without departing from the spirit of my invention; hence I do not wish to be understood as limiting myself to the exact form, construction, arrangement and combination of parts herein 55 shown and described or uses mentioned.

What I claim as new and desire to secure by Letters Patent is:

60 1. In a shoe heel of the kind described and in combination, a molded tubular body part recessed at the top and bottom to provide shoulders, wooden plates for the top and bottom conforming in size and shape to closely fit in the recesses in the body part and over-

lie said shoulders, and a wooden post connecting said plates, said post provided with sleeves at its ends flanged over and overlying the outer faces of the plates.

2. In a heel of the kind described and in combination, a molded body part of a phenolic condensation product provided with an opening extending entirely through the same from top to bottom and countersunk at the top and bottom about the opening to provide 75 shoulders thereat, a pair of wooden plates of a size and contour to fit into said countersunk ends and rest upon said shoulders with the outer faces of the plates flush with the outer faces of the top and bottom of the body 80 part, said plates each provided with an opening therethrough, and a post member of a length to extend from substantially the outer face of one plate to the outer face of the other plate, said post having a metal flange at each 85 end to provide an outwardly extending flange overlying the outer faces of the plates.

3. In a heel of the kind described and in combination, a molded body part of a phenolic condensation product provided with an 90 opening extending entirely through the same from top to bottom and countersunk at the top and bottom about the opening to provide shoulders thereat, a pair of wooden plates of a size and contour to fit into said countersunk ends and rest upon said shoulders with the outer faces of the plates flush with the outer faces of the top and bottom of the body 95 part, said plates each provided with an opening therethrough and slightly countersunk 100 about the same at the exterior of the plates, and a wooden post member of a length to extend from substantially the outer face of one plate to the outer face of the other plate, said post provided with a metal sleeve at each 105 end secured thereto and projecting slightly beyond the ends of the post and of a length to provide an outwardly extending flange fitting into said countersunk portions on the outer faces of the plates.

4. In a heel of the kind described and in combination, a molded tubular body part of a material impervious to moisture and capable of receiving a high finish, said body part recessed at the top and bottom to provide shoulders, top and bottom plates arranged in said recesses with the outer faces thereof flush with the outer faces of the body part, the top face of the body part and top plate being dished, the bottom face of the body part and bottom plate being flat, a post extending through the opening in the body part and through the plates and engaging the outer faces thereof, said plates being of a material penetrable by nails or equivalent fastening means, a lower lift of suitable material conforming to the shape of the bottom of the body part and secured to the bottom plate.

5. In a heel of the kind described and in 130

combination, a molded tubular body part of a material impervious to moisture and capable of receiving a high finish, said body part recessed at the top and bottom about the opening through the same to provide shoulders, top and bottom plates seated in said recesses and closely fitting the same with the outer faces thereof flush with the outer faces of the body part, the top face of the body part and top plate being dished, the bottom face of the body part and bottom plate being flat, a post extending through the opening in the body part and through the plates and having means for overlying and engaging the outer faces thereof, said plates and post being of a material penetrable by nails or equivalent fastening means, and a lower lift of suitable material conforming to the shape of the bottom of the body part and secured to the bottom plate.

6. In a shoe heel of the character described and in combination, a molded tubular body part having a countersunk portion formed adjacent the top and bottom ends thereof to provide shoulders extending around the opening therethrough, plates in said countersunk portions and engaging said shoulders, and a connecting member having portions adjacent its ends adapted to extend through said plates and engageable with the outer faces thereof.

In testimony whereof, I have hereunto signed my name.

ISIDORE SIMON.
